DESIGN FOR A BACK FOR AN ELECTRIC SWITCH

Earl J. Baumgardner, Marion, Iowa, assignor to
H. A. Douglas Mfg. Co., Bronson, Mich., a cor-
poration of Michigan

Application December 12, 1944, Serial No. 116,856

Term of patent 14 years

(Cl. D26—13)

To all whom it may concern:

Be it known that I, Earl J. Baumgardner, a citizen of the United States and a resident of Marion, in the county of Linn and State of Iowa, have invented a new, original, and ornamental Design for a Back for an Electric Switch, of which the following is a specification, reference being had to the accompanying drawing, forming part thereof.

Figure 1 is a perspective view of a back for an electric switch, showing my new design;

Figure 2 is a top plan view of the switch back illustrated in Figure 1;

Figure 3 is an end view of the switch back; and

Figure 4 is a side view of the switch back.

I claim:

The ornamental design for a back for an electric switch, as shown.

EARL J. BAUMGARDNER.
